(57) **CLAIM**

The ornamental design for a solar lamp with petal shade, as shown and described.

DESCRIPTION

FIG. 1 is a perspective view of the solar lamp with petal shade of the present invention;

FIG. 2 is a front elevation view thereof; the rear elevation view being a mirror image thereof;

FIG. 3 is a left side elevation view thereof; the right side elevation view being a mirror image thereof;

FIG. 4 is a bottom plan view thereof; and,

FIG. 5 is a top plan view thereof.

The broken lines shown on the drawings depict portions of the solar lamp that form no part of the claimed design.
